(57) **CLAIM**

The ornamental design for a cap closure cover, as shown and described.

DESCRIPTION

FIG. 1. is a perspective view of a cap closure cover, showing my new invention;

FIG. 2. is a bottom perspective view thereof;

FIG. 3. is a top view thereof;

FIG. 4. is a front view thereof; and,

FIG. 5. is a side view thereof.

The dashed lines are for illustrative purposes only and do not form part of the invention.
